BOILER CLEANER

De Los E. Hibner, Jr., and Theodore M. Bruback,
Du Bois, Pa.

Application March 10, 1930. Serial No. 434,601

7 Claims. (Cl. 122—392)

This invention relates to soot cleaners for boilers or the like, and aims to provide certain improvements therein.

The invention is particularly directed to that type of soot cleaner wherein a so-called cleaner element is used which comprises a pipe extending in among the boiler tubes, from which steam or other cleaning fluid is ejected over and around the tubes. The cleaner element is usually provided with suitable nozzles for this purpose.

There are at present in use large water tube boilers wherein the number of tubes in the width of the boiler is so great that a cleaner element of the ordinary diameter has not sufficient steam

carrying capacity to clean the entire number at one operation. In many instances an increase in diameter of the cleaner element to increase its steam carrying capacity is not permissible because of the lack of space between the tubes or for other reasons. According to the present invention in its preferred form we provide a device in which the entire group of tubes can be cleaned by shifting the cleaner element longitudinally and blowing steam or other fluid over alternate or successive sections of the tube system. By this means a single long element, projecting into the boiler from one side, is made to accomplish the functions of two shorter elements extending into the boiler from opposite sides.

The invention also includes a construction in which the valve travels to its open position and then to its closed position coincidently with and preferably actuated by the longitudinal movements of the cleaner element. In the preferred form of the invention the valve is closed when the cleaner element is in mid-position, from which position it is capable of movement in either direction to perform a cleaning operation.

The invention also includes several other features of improvement which will be hereinafter more fully described.

In the drawings which illustrate several forms of the invention,—

Figure 1 is a longitudinal section, partly in elevation, of the preferred form of the operating mechanism embodied in our invention.

Fig. 2 is a section of Fig. 1 on the line 2—2 of that figure.

Fig. 3 is a section of Fig. 1 on the line 3—3.

Fig. 4 is a view of a modified form of the invention.

Fig. 5 is a section taken on line 5—5 in Fig. 4.

Referring first to Figs. 1 to 3, let A indicate a cleaner element which comprises a tube extending through a boiler wall B in the usual manner into

the interior of the boiler. The cleaner element is provided with a series of laterally arranged nozzles of the usual or any desired construction, and if the boiler is a large one, so that full advantage of the invention may be secured, the cleaner element is extended in a transverse direction over the entire bank of tubes. But in this case the nozzles may be so arranged that they are approximately twice the distance apart as is customary, so that alternate areas of the tube surfaces are cleaned at one position of the element. As previously stated, by shifting the element longitudinally the uncleaned alternate sections or areas are cleaned when the element is shifted.

According to the preferred construction of the invention the outer end of the element A or its equivalent extends into a steam chamber C, into which a steam pipe D leads, which feeds steam from the boiler into the chamber. Any other cleaning fluid may, of course, be substituted. Preferably the element A not only extends into the chamber, but passes through it, as best seen in Fig. 1, its outer end being closed and exposed to atmosphere. To make a tight joint on each side of the steam chamber, packing glands E and F are utilized. The passage of steam from the steam chamber C to the interior of the cleaner element is permitted by openings G formed in the element, so that in any position of the element steam may flow from the chamber into the element. Steam flow to the chamber C, however, is controlled by a valve H coacting with a seat I, the latter being formed in the bottom wall of the chamber. The valve seat I is preferably of oval form with its longest dimensions extending transversely of the element, so that the maximum opening for a given movement of the valve is obtained. The valve H is mounted upon a carrier which may be variously constructed, that shown comprising a rod K, the rod and valve being adapted to reciprocate in a valve chamber L arranged below the seat I. The movements of the rod are in the construction shown imparted from the exterior of the valve chamber, and the rod is hence provided with a packing gland M where it passes out of the valve chamber.

In the preferred construction the valve movements through the medium of the rod K are controlled, and preferably actuated, by the movements of the cleaner element A. Thus in the preferred construction the end of the rod is connected to a bracket N which is held in place on the element A by two nuts O and P screwing on exterior threads on the element, and by means of which an exact longitudinal adjustment may

be attained. The bracket, however, does not fixedly engage the element, the construction being such that the element can rotate without turning the bracket, the two nuts O and P forming bearing surfaces for the bracket.

In the preferred construction of the invention which has been thus far described it is necessary to impart to the cleaner element two movements, one a rotary movement about its axis to cause the steam issuing from the nozzles to sweep the boiler tube surfaces as is customary, and the other a longitudinal movement to cause the cleaner to shift its position lengthwise. It will be, of course, understood that these movements may be quite distinct, or may be compounded so that both may take place either wholly or partly during the same time.

In the present form of the invention we provide means whereby a single operative member, such as the sheave wheel Q, may act to produce the different motions required by the invention. The wheel Q is fixedly mounted upon a shaft R, which shaft rotates in a bearing S formed on a bracket T connected with the steam chamber wall. The shaft R has also fixedly mounted upon it a pinion U which meshes with a pinion V fixed upon a longitudinally extended operating screw W which at one end has a bearing in the wall of the steam chamber and at the other end has a bearing in a plate X which surrounds the cleaner element and which is held fixedly in position by bolts Y which connect it with the lower wall of the steam chamber. It results from this construction that when the sheave wheel Q is turned by a chain or the like the screw W is also turned, and as the pinions U and V are of the same diameter, the screw W will rotate once for each rotation of the sheave wheel Q, although, of course, this may be varied as desired.

At the extreme left-hand of the screw W the latter carries a small pinion A' which meshes with a large gear B' keyed to the cleaner element in such manner that a relative sliding motion is permitted. The proportionate diameters of the pinion and gear may be varied, but they are shown as approximately 1 to 6, so that for one rotation of the screw W, and hence of the sheave wheel, there is a one-sixth of a rotation of the gear wheel, and consequently the cleaner element. As is customary in this art the angular movement of the cleaner element is usually an oscillating one, the element rotating back and forth through an arc which is selected as that being best adapted for each element. Ordinarily the arc of oscillation is less than 180°, and in many cases it is much less; occasionally, however, this angular movement will be exceeded. The preferred means for limiting the angular movement to definite arcs will be hereinafter referred to.

By preference the screw W is utilized for imparting a longitudinal movement to the element, and this is shown as accomplished through the medium of travelling nut members C' and D' which engage the screw, as shown in Fig. 1, and which, as best seen in Fig. 2, also slide along a fixed guide bar E' which is held between the plate X and the wall of the steam chamber. This construction prevents the turning of the nut members as the screw W turns and compels them to travel to the right or to the left as the sheave is turned. Motion is transmitted from one or the other of the nut members C' D' to the cleaner element by means of an upper extension F' of the bracket N which is preferably formed with

an eye G' encircling the screw W between the two nut members.

It results from this construction that if the parts be assumed to be in the position of Fig. 1, and the sheave wheel be rotated in a direction to move the nuts C' D' to the right, the element will be moved to the right until the valve H is opened. This position is determined in the structure shown by contact of the stop surface H' of the bracket F' with a stop screw I' carried by the wall of the steam chamber. When the parts are in this position further movement of the element to the right is prevented. During this opening movement of the valve to the right, the cleaner element also incidentally turns in the construction shown, but as this turning movement is accompanied by only a partial admission of steam through the progressively opening valve it is preferably not relied upon for cleaning purposes.

The actual cleaning operation with the element at its extreme right is accomplished by reversing the direction of the sheave wheel, this carrying the two nuts to the left and leaving the element in its extreme right-hand position with the valve open, in which position it is maintained so far as longitudinal movement is concerned until the nut D' strikes the eye G' and moves the element to the left to its mid position, wherein the valve H is closed. During this movement, when the valve is wide open, the cleaning operation is mainly performed. This is due to the fact that while the element is retained longitudinally in fixed position, it is nevertheless, being rotated by the pinion A' at the end of the screw W which rotates the gear B' and hence the cleaner element. A continued movement of the sheave in the same direction will result in the nut D' being forced further to the left and with it the bracket F' and cleaner element until the valve is wide open and lies to the left of this seat. When a stop surface J' contacts with a stop bolt L' formed on the plate X, the valve has reached its wide open position, and upon a reversal of the sheave wheel the element again performs its angular cleaning movement.

It is to be noted, however, that the latter angular cleaning movement occurs during the time when the element is shifted to the left, so that the nozzles lie over a fresh section of boiler tubing. It hence follows from the operation thus described that the cleaner element has two operative positions, one at its extreme limit of movement at the right and the other at its extreme limit of movement at the left. It hence cleans approximately one-half of the tube surface on each of these movements. While the cleaner is preferably designed to extend entirely across the boiler, the arrangement of nozzles is preferably such that they are spaced usually about twice the customary distance, so that at the finish of the first of the two cleaning operations, there will be alternate areas of cleaned and uncleaned surfaces while at the second operation the uncleaned surfaces will be cleaned. By the use of the present invention, therefore, it is not necessary to employ a cleaner element of sufficient internal diameter to clean the entire surface at one time. A considerably smaller element can be used which has only sufficient steam-carrying capacity to clean one-half the required area at one time.

It will be observed that in the preferred form of the invention these two cleaning operations are attained by a single sheave wheel which is very simple to actuate. That is to say, starting

from a middle position, wherein the valve is closed, the sheave wheel is simply rotated in one direction until it stops, then in the opposite direction until it stops, and then to the central position. It is, of course, possible, to clean and reclean one half the area of the tubes by special manipulation of the element from the central position to one extreme with the valve open, and then by reversing the sheave to continue to oscillate the element without moving it lengthwise. This method of operation will ordinarily not be necessary or desirable.

It will be observed that in the normal operation of the preferred construction shown the effective cleaning is performed during the interval when neither of the nuts C' D' is in contact with the eye G'; that is to say, during the time that one nut is travelling away from the eye and the opposite nut is travelling toward it. The number of rotations of the screw thus availed of for effective angular movement depends entirely upon the adjustment of the two nuts C' D'. If a small angular movement is hence required, the nuts will be adjusted toward each other, and if a large angular movement, the nuts will be separated. By reference to Fig. 2, it will be seen that the adjustment of the nuts along the screw is provided for by forming the nut in two parts, C² C³, connected by bolts C⁴. When the bolts are loosened, the nuts can be slid along the screw to the proper position.

The construction shown in Fig. 1 is so designed that when the nuts are separated to their maximum, the element is permitted a full rotation of 360° of active operation, a sufficient amount of travel beyond this being permitted at the beginning and end of the operation to open and close the valve. If in the construction shown the pinion A' has four teeth and the gear B' has forty-eight teeth and the screw W is provided with three threads to the inch, the effective separation of the two nuts C' and D' to secure an active cleaning operation of 360° would be four inches. Such effective separation would be obtained by measuring the distance between the two nuts and subtracting the thickness of the eye G'. If a ninety degree angular movement is required, the effective separation between the two nuts would be one inch. The two nuts in effect constitute an adjustable lost motion connection for moving the element.

Since in the type of cleaner which is provided by the preferred form of the invention, the valve is closed in an intermediate position, our invention provides an index or indication which shows when this position has been reached. This indicator may be any one of the various types of indicators which are known in the art, either audible or visible, or otherwise. We prefer, however, to use an audible signal, such as the whistle N', which is connected with the steam chamber C and sounds during the operation of the device. A cessation of the operation silences the whistle.

In the construction shown in Fig. 4, results are accomplished which are similar to those with regard to Figs. 1 to 3, and the device bears a close resemblance to that construction with the exception that two sheave wheels are required.

In Fig. 4 A² is the cleaner element, C² is the steam chamber, D² the steam supply pipe, H² the valve, and I² the valve seat. W² is a screw shaft which is turned by a sheave Q² and which causes a nut G² to travel longitudinally of the cleaner element, the nut being formed on a bracket N² loosely connected with the cleaner

element, which bracket is connected to the valve H² by a valve rod K². The cleaner element does not extend completely through the steam chamber C², but is provided with an open end for admission of steam. A single packing gland E² 80 is hence used.

The element is turned by a gear B³ which is rotated by a pinion A³ carried at the end of a shaft W³ which is adapted to be rotated by a second sheave wheel Q³. The shaft W³ is arranged within the screw W² which is made hollow for this purpose, and the two sheaves Q² and Q³ are concentrically arranged.

As in the construction of Fig. 1 the valve and element occupy an intermediate position when the valve is closed. When it is desired to operate the element in its right-hand position the sheave wheel Q² is operated to cause the nut, element, and valve to travel to the right. When the extreme right hand position is reached, wherein a stop H³ engages an abutment I³, the valve is fully open, and the cleaner is then rotated by rotating the sheave wheel Q³. Backward and forward oscillation may continue as long as desired in this position, and when the cleaning operation is finished, the sheave wheel Q² is again operated to cause the nut G², the element A² and the valve H² to travel to their extreme left position, wherein a stop J³ engages an abutment L³. This movement brings the nozzles of the cleaner over the uncleared areas of the bank of tubes, whereupon the actual cleaning operation may be accomplished by rotating the sheave wheel Q³.

In the construction just described the longitudinal movement of the cleaner is limited by the travel of the nut, and the latter may be made adjustable if desired. The degree of rotative or angular movement of the cleaner is determined by a stop A⁴ carried by gear B³ and which is designed to contact with a stop B⁴ carried upon a ring D⁴ which fits nonrotatably into the plate X⁴. The stop A⁴ also engages a stop C⁴ carried upon a cover plate E⁴, the edge of which is provided with a series of notches F⁴ around its periphery, in which notches the heads of cap screws G⁴ fit. The ring D⁴ is provided with a series of holes H⁴ in which a pin or pins I⁴ carried by the cover plate E⁴ fit. It will be observed by the foregoing construction that the angular position of the stop B⁴ on the ring D⁴ may be adjusted by locating the pins I⁴ in appropriate holes H⁴ in the ring D⁴. It will also be observed that the angular position of the stop C⁴ may be adjusted by bringing the appropriate recesses F⁴ in coincidence with the cap screws G⁴. By this simple adjustment any location of the stops which is desired may be obtained, so that not only any degree of angular movement of the cleaner may be obtained, but also that this arc of travel may be located at any desired points.

Our invention also presents an improvement in valves which is shown in each of the constructions illustrated. In the preferred construction the valve H or H² is mounted in a carrier A⁵ which preferably has a squared opening B⁵, the valve having a similarly shaped shank C⁵. The valve is held against its seat not only by steam pressure, but by a spring D⁵ which presses against a supporting surface E⁵, shown as carried by a plate F⁵, which is threaded to receive the steam pipe D. The supporting surface E⁵ may be formed directly on the plate, or may be formed upon a wear-block G⁵ fitted to the plate as shown. A cup H⁵ 150

is preferably interposed between the spring and the plate. It will be understood that the plate has openings on each side which the supporting surface E^5 bridges. By interposing gaskets I^5 of various thicknesses between the plate and the wall of the steam chamber any desired adjustment of the supporting surface with relation to the valve may be obtained. Or a gasket may be used which has sufficient compressibility to be adjusted by the manipulation of the screw bolts holding the plate F^5 to the wall of the steam chamber. The valve seat I or I^2 is preferably oval and flat on its under side, and the non-rotative connection between the valve and its carrier permits the use of an oval valve without danger of angular movement of the latter.

The latter construction is adapted for the purpose of obtaining a quick opening of sufficient valve area to supply the requisite amount of steam and permits a cleaning action if desired during a considerable part of the longitudinal travel of the element.

While we have shown and described several forms of the invention, it will be understood that we do not wish to be limited thereto, since various changes may be made therein without departing from the spirit of the invention.

What we claim is:

1. A cleaner for boilers or the like, comprising a cleaner element which is mounted for rotation and longitudinal movement, a source of fluid, a valve for controlling the passage of fluid to the cleaner element, and a connection between said valve and said cleaner element, said connection having means to transmit the longitudinal movements of the cleaner element to the valve, and said connection permitting relative rotative movements between itself and the cleaner element.

2. A cleaner for boilers or the like, comprising a longitudinally movable cleaner element adapted also for rotation, a screw, gearing turned by said screw for rotating the element, means including a lost motion device operated by said screw for longitudinally moving the element, said lost motion device being so arranged that said screw and gearing is operable to rotate the element without imparting longitudinal movement thereto.

3. A cleaner for boilers or the like having a single valve seat and a reciprocating valve and means for moving the valve in two directions away from its seat to open the latter, and signal means for indicating the positions of the valve and seat.

4. A cleaner for boilers or the like having a single valve seat and a reciprocating valve and means for moving the valve in two directions away from its seat to open the latter, and signal means for indicating the positions of the valve and seat, said means operating when the valve is open.

5. A cleaner for boilers or the like having a single valve seat and a reciprocating valve and means for moving the valve in two directions away from its seat to open the latter, and signal means for indicating the positions of the valve and seat, said means operating when the valve is open and comprising a whistle connected with the cleaning fluid chamber.

6. A cleaner for boilers or the like, comprising a cleaner element constructed and arranged for longitudinal movement to different blowing positions, a steam chamber in constant communication with said element, a valve so constructed and arranged as to be moved by the element in its longitudinal movements for supplying steam to said chamber in each of said blowing positions, a screw having a pinion fixed on the end thereof, a gear meshing with said pinion and so connected to said element as to impart rotation thereto and provide for longitudinal sliding of the element relatively to the gear, a pair of nuts moved by said screw, and a member located between said nuts and so connected to said element as to longitudinally move the same when engaged by said nuts.

7. A cleaner for boilers or the like, comprising a cleaner element constructed and arranged for longitudinal movement to different blowing positions, a steam chamber in constant communication with said element, a valve so constructed and arranged as to be moved by the element in its longitudinal movements for supplying steam to said chamber in each of said blowing positions, a screw having a pinion fixed on the end thereof, a gear meshing with said pinion and so connected to said element as to impart rotation thereto and provide for longitudinal sliding of the element relatively to the gear, a pair of nuts moved by said screw, and a member located between said nuts and so connected to said element as to longitudinally move the same when engaged by said nuts, and said nuts being adjustable to vary the rotation of said element.

DE LOS E. HIBNER, JR.
